United States Patent Office

Des. 192,770
Patented May 8, 1962

192,770

OUTBOARD MOTOR

Carl Erik Sixten Andersson-Sason, Solna, Sweden, assignor to Aktiebolaget Electrolux, Stockholm, Sweden, a corporation of Sweden

Filed Sept. 16, 1960, Ser. No. 62,376

Term of patent 14 years

(Cl. D71—1)

FIG. 1

FIG. 2

Des. 192,770

PAGE 2

FIG. 3

FIG. 4

FIG. 5

FIG. 1 is a rear perspective view of an outboard motor showing my new design;

FIG. 2 is a front perspective view thereof;

FIG. 3 is a front elevational view thereof;

FIG. 4 is a top plan view thereof; and

FIG. 5 is a side elevational view thereof.

What I claim is:

The ornamental design for an outboard motor, as shown.
